AUTOMOBILE FLOOR MAT OR SIMILAR
ARTICLE

Chester E. Sherman, Dallas, Tex.

Application April 15, 1950, Serial No. 9,237

Term of patent 7 years

(Cl. D9—6)

To all whom it may concern:

Be it known that I, Chester E. Sherman, a citizen of the United States, residing at Dallas, in the county of Dallas and State of Texas, have invented a new, original, and ornamental Design for Automobile Floor Mat or Similar Article, of which the following is a specification, reference being had to the accompanying drawing, forming part thereof:

Figure 1 is a top plan view of an automobile floor mat or similar article embodying my new design, and

Figure 2 is an enlarged fragmentary perspective view thereof.

I claim:

The ornamental design for an automobile floor mat or similar article, substantially as shown.

CHESTER E. SHERMAN.
